UNITED STATES PATENT OFFICE

JAMES C. DAY, OF SOUTH ORANGE, NEW JERSEY, ASSIGNOR TO THE WHITEHEAD AND HOAG COMPANY, OF NEWARK, NEW JERSEY, A CORPORATION OF NEW JERSEY

BUTTON RECEPTACLE

Application filed July 16, 1928. Serial No. 293,133.

This invention relates to a new and improved button receptacle. When licenses are issued by States or municipalities for the privilege of conducting certain activities such as hunting and fishing it is frequently a requirement of law that the possessor of the license carry on his person and exposed to view indicia stating the fact that he is a possessor of the required license. He is also required to carry with him the license itself, and the main object of my invention is to provide a device which may be easily attached to the clothing of the bearer, which can carry on its face any desired indicia and which itself constitutes a convenient receptacle in which a license may be carried.

Another object is to produce a device of this character in a cheaper and better way than has hitherto been possible.

Other objects and advantages relate to the size, shape and arrangement of parts all as will more fully appear from the following description taken in connection with the accompanying drawings in which:

25 Figure 1 is a front elevation of my device.

Figure 2 is a rear elevation of my device.

Figure 3 is a section on line 3—3 of Figure 1.

Figure 4 is a section on line 4—4 of Figure 1.

Figure 5 is a section on line 5—5 of Figure 3.

My device consists of a front plate —1— having a rearwardly and inwardly extending annular flange and adapted to be covered by a sheet of celluloid or other appropriate material —2— upon which may be placed any desired indicia. The sheet —2—, as perhaps may best be seen at —a— in Figure 3, is return bent on its edge to enclose the annular flange of front plate —1— and is confined between the annular flange of front plate —1— and the outer edge of a back plate —3—. Back plate —3— is dish shaped

40 having a forwardly and outwardly extending annular flange —4— adapted to coact with the annular flange of front plate —1— to confine the sheet —2— in position.

Back plate —3— has opposed slots —5— and —6—. A pin —7— has an oppositely

deflected portion —8— positioned in a groove 8' in the front surface of back plate —3— having one end extending through slot —6— and formed into a coil —9— from which extends the pin portion —10— to engage a loop —11— formed upon the opposite end of portion —8—. Loop —11— extends outwardly through slot —5—. A lug —12— is formed from a portion of back plate —3— and is return bent on back plate —3— to rest against portion —8— of pin —7— to hold pin —7— in position. A pair of locking lugs —13— and —14— are formed in back plate —3— and are return bent to engage lug —12— to hold the same in position. An aperture —15— is formed in back plate —3— adjacent the lower edge thereof.

When the device is in use the license which is to be carried is folded to the proper size and then is inserted between front plate —1— and back plate —3— through the opening —16— which was formed when the lug —12— was return bent on back plate —3—. When it is desired to remove the license the same is easily accomplished by inserting a finger in aperture —15— and pushing the license upwardly and out through opening —16—. Aperture 15 also serves the purpose of permitting the escape of any moisture which may enter opening —16—.

The pin —7— forms a convenient means of attaching the device to the clothing of the bearer.

It will be understood that the exact size and position of lugs 12, 13 and 14 may be varied as desired as may the size of aperture 15 and opening —16—. It will also be understood that the device may, if desired, be constructed in shapes other than the circular shape here illustrated, for although I have shown and described a specific structure and form of part as an exemplification of an embodiment of my invention I do not desire to restrict myself to the exact size, shape or relation of parts as various changes may be made within the scope of the appended claims.

What I claim is:

1. In a device of the class described, a front plate, a back plate connected and having its central portion in spaced relation thereto to

form a pocket, a fastening means positioned in the back plate, an aperture through the back plate communicating with the pocket to permit the introduction of an article therein, a portion of the back plate return bent on itself to hold the fastening means in position, and additional portions of the back plate return bent to hold in position the first mentioned return bent portion.

10 2. In a device of the class described, a front plate, indicia carrying material positioned on one face of the front plate, a back plate having its central portion in spaced relation to the front plate to form a pocket, the edge 15 of said indicia carrying material being positioned between the front plate and the back plate, a fastening means positioned on the back plate, an aperture in the back plate communicating with the pocket to permit the introduction of an article therein, said back 20 plate having a portion return bent to hold the fastening means in position.

25 3. In a device of the class described, a front plate, indicia carrying material positioned on one face of the front plate, a back plate having its central portion in spaced relation to the front plate to form a pocket, the edge of 30 said indicia carrying material being positioned between the front plate and the back plate, a fastening means positioned on the back plate, an aperture in the back plate communicating with the pocket to permit the introduction of an article therein, said back plate having a portion return bent to hold the 35 fastening means in position, and additional portions of the back plate being return bent and superimposed upon the first mentioned return bent portion.

40 4. In a device of the class described, a front plate, a back plate connected and having its central portion in spaced relation thereto to form a pocket, a fastening means positioned in the back plate, an aperture through the back plate communicating with 45 the pocket to permit the introduction of an article therein, and a portion of the back plate return bent on itself to hold the fastening means in position, and a second aperture in the back plate in spaced relation to the first named aperture and communicating with the pocket.

50 5. In a device of the class described, a front plate, a back plate connected and in spaced relation thereto to form a pocket, a fastening means positioned in the back plate, an aperture through the back plate communicating with the pocket to permit the introduction of an article therein, and a portion 55 of the back plate return bent on itself to hold the fastening means in position, additional portions of the back plate return bent to hold in position the first mentioned return bent portion, and a second aperture in the 60 back plate in spaced relation to the first 65

named aperture and communicating with the pocket.

6. In a device of the class described, a front plate, indicia carrying material positioned on one face of the front plate, a back plate having its central portion in spaced relation to the front plate to form a pocket, the edge of said indicia carrying material being positioned between the front plate and the back plate, a fastening means positioned on the back plate, an aperture in the back plate communicating with the pocket to permit the introduction of an article therein, said back plate having a portion return bent to hold the fastening means in position, and a second aperture in the back plate in spaced relation to the first named aperture and communicating with the pocket.

7. In a device of the class described, a front plate, indicia carrying material positioned on one face of the front plate, a back plate having its central portion in spaced relation to the front plate to form a pocket, the edge of said indicia carrying material being positioned between the front plate and the back plate, a fastening means positioned on the back plate, an aperture in the back plate communicating with the pocket to permit the introduction of an article therein, said back plate having a portion return bent to hold the fastening means in position, additional portions of the back plate being return bent and superimposed upon the first mentioned return bent portion, and a second aperture in the back plate in spaced relation to the first named aperture and communicating with the pocket.

8. In a device of the class described, a front plate, a back plate connected and having its central portion in spaced relation thereto to form a pocket, a fastening means having its central portion positioned in a reverse-curved groove in the back plate, an aperture through the back plate communicating with the pocket to permit the introduction of an article therein, and a portion of the back plate return bent on itself to hold the fastening means in position.

9. In a device of the class described, a front plate, a back plate connected and having its central portion in spaced relation thereto to form a pocket, a fastening means positioned in a groove in the back plate, an aperture through the back plate communicating with the pocket to permit the introduction of an article therein, a portion of the back plate return bent on itself to hold the fastening means in position, and additional portions of the back plate return bent to hold in position the first mentioned return bent portion.

10. In a device of the class described, a front plate, a rearwardly dished back plate spaced at its central portion from the front plate and secured at its edge to the front

plate and having an opening therethrough leading to the space between the plates, said space being bordered at the opening by a portion of the upstanding annular rim of the back plate.

5 11. In a device of the class described, a front plate, a rearwardly dished back plate spaced at its central portion from the front plate and secured at its edge to the front plate and having an opening therethrough leading to the space between the plates, said space being bordered at the opening by a portion of the upstanding annular rim of the back plate, said back plate being formed with 10 a finger opening spaced from the first named opening and communicating with the space between the plates.

15 In witness whereof I have hereunto set my hand this 2d day of July, 1928.

20 JAMES C. DAY.
